PRINTING PROCESS

Homer L. Bishop, Dayton, Ohio, assignor of one-half to Earl E. Stansell, West Carrollton, Ohio

Application November 26, 1934, Serial No. 754,818

12 Claims. (Cl. 41—25.5)

This invention relates to the method of and device for preparing and supporting printing plates, and particularly to the method of making backing to be inserted between the plate and the packing cylinder in the packing thereon.

In the preparation of printing plates, especially plates for reproducing pictures, photographs, drawings, illustrations and the like, it is desirable to emphasize certain portions of the plate and to relieve other portions so as to properly reproduce the contrasts found in the original. This is generally referred to as "make-ready". In the past, several methods have been employed for accomplishing this result. One method includes the building up of patches mounted intermediate the plate and the mounting for emphasizing certain portions of the plate, permitting other portions to be depressed. The preparation of the patches involves considerable labor by trained experts which enhances the cost of the printing. These patches may be made from a plurality of prints wherein areas of differing extent are cut from all but one of the prints, which one forms the base upon which the remaining portions of the cut prints are pasted. The print with all but the solid portion removed is placed next to the uncut print, the solid portion of which registers with the solid portion of the superimposed print. The succeeding print may have the light areas in addition to the high-light areas cut away, etc.

An object of this invention is to provide a "make-ready", made from a laminated sheet, the portions removed from each lamina varying to properly emphasize certain portions of the plate when used as a "make-ready".

Another object of this invention is to reproduce a cut upon a laminated sheet cutting out of this print the portions to be relieved, as indicated by the print thereon, and using this cut lamination as a "make-ready".

Another object of this invention is to provide a laminated structure, the laminations of which may be identified from one another to expedite the preparation of the "make-ready".

Another object of this invention is to provide a "make-ready" that is cheap, efficient, dependable, easily and accurately produced.

With the above primary and other incidental objects in view, as will more fully appear in the specification, the invention consists of the features of construction, the parts and combinations thereof, and the mode of operation, or their equivalents, as hereinafter described and set forth in the claims.

5 In the drawings, Fig. 1 discloses a plurality of

sheets or laminae before assembling into a laminated structure. Fig. 2 shows a laminated structure ready for the process. Fig. 3 shows the laminated structure upon which the print of the plate is impressed. Figs. 4, 5 and 6 disclose the laminated sheet in successive steps of preparation for a "make-ready" or a backing member for a printing plate as the case may be.

As referred to above, it has been old to place "make-readys" upon the packing cylinder under the draw sheet and in registry with the plate to emphasize certain portions of the cut, relieving other portions so as to properly reproduce the cut, but in the prior art the "make-ready" has been built up patches, which requires accurate workmanship on the part of skilled workmen.

In the process of my invention a laminated sheet of material, preferably made of laminations of different colors, is impressed and the cut reproduced on the surface whereby the high lights may be removed in their entirety from the laminations, intermediate shades removed from one or more layers so as to provide a "make-ready" to be mounted intermediate the plate and the packing cylinder, preferably lodged in the packing under the draw sheet, which permits the high lights and the intermediate shaded areas to be relieved in varying degrees so as to properly emphasize the high lights and the shaded areas of the print.

Referring to the drawings, the reference character 10 indicates one lamina which has been designated as white; 12 is a second lamina indicated as green; and 14 a third lamina shown as yellow, which when assembled forms a laminated sheet 16 preferably having a smooth surface.

In the preparation of the laminated sheets 16 from the laminae 10, 12 and 14, it is preferable to coat the sheets with a binding material which will hold the sheets together under ordinary conditions but will fail more readily than the material of the laminae, so that portions of the laminae may be removed by failure of the binding material without a failure of the laminae per se. For a binding material, compounds including wax have been found to give satisfactory results. Although the illustrative drawings show a laminated sheet of only three sheets, any number of sheets may be used, depending entirely upon the demands.

The plate to be used has, for the purposes of illustration, a hat thereon which is printed upon the surface of the laminations 16.

The Figure 18 in the modification disclosed shows a hat having high light areas 20, the com-

paratively light areas 22, the comparatively dark areas 24, and the extremely dark areas 26. In order to properly reproduce this hat from a cut it may be necessary to relieve the high light areas

- 5 20 from the plate by a thickness corresponding to the thickness of three laminae. It may also be desirable to relieve the comparatively light areas 22 by a thickness corresponding to two laminae and to relieve the comparatively dark areas 24
- 10 by a thickness corresponding to one lamina, leaving the extremely dark areas 26 intact.

To accomplish this the high light areas are removed from all the laminations as shown by the reference character 30 in Fig. 4. This may be easily and quickly done by the use of a printer's spot knife or any other suitable cutting implement. The comparatively light area 22 should be backed by one thickness of a lamination. This is accomplished by cutting through laminations 20 10 and 12, that is the white and the green, leaving the yellow lamination intact under the areas 22 as shown by the reference character 32 in Fig. 5. The comparatively dark portion 24 is next cut away through the white area down to the green, 25 as shown by reference character 34 in Fig. 6.

The laminated sheet 16 is now ready to be placed intermediate the draw sheet and the packing sheets found upon the packing cylinder. This make-ready is placed in registry with the corresponding plate the same as when patches are used. From this it is seen that the high light areas 20 are depressed a distance corresponding to the thickness of three laminations, the comparatively light areas 22 a distance corresponding to the thickness of two laminations and the comparatively dark areas 24 a distance corresponding to the thickness of one lamination. For the purpose of illustration, the laminated sheets 10, 12 and 14 are greatly exaggerated as to thickness, 40 as each sheet should be only a few thousandths of an inch thick. The laminated sheet is not affected by variations of humidity of the air, due to the wax-like coating which makes it impervious to moisture.

45 From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

50 While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the 65 appended claims.

Having thus described my invention, I claim:

1. The process of preparing make ready, including the steps of printing upon united laminated sheet material from a plate, cutting and removing portions of laminations while united underlying certain predetermined areas of the print, inserting said laminated material having portion thereof removed intermediate the plate and the packing cylinder with the removed portions in registry with corresponding portions of the plate
- 75

to effect relative depression and elevation of different portions of the face of the plate.

2. The process of preparing a make ready, including the steps of printing upon a united laminated sheet of material, removing portions bodily from the laminated sheets while united to emphasize gradations of light on the cut and placing the remainder of the united laminated sheet in registry with the plate.

3. The process of preparing a make ready, including the steps of reproducing the cut on the plate upon a sheet of laminated material held in a united body, removing portions bodily from the laminated body while united so that as the remainder thereof is placed in registry with the plate the gradations in light are emphasized.

4. The process of preparing a make ready, including the steps of reproducing the cut on the plate upon a sheet of united laminated material having strata held together with a binding material, peeling portions thereof while united to correct improper shading when the remainder is used as a make ready.

5. The process of producing a make ready, including the steps of securing a plurality of sheets together into a laminated sheet, removing portions bodily from the laminated sheet while held together whereby the remainder may be used as a make ready.

6. The process of producing a make ready, including the steps of securing a plurality of differently colored sheets together into a united laminated sheet, peeling portions from said laminated sheet while united so as to have a variegated colored make ready, the colored portions corresponding to shade gradations on the plate.

7. The process of producing a make ready, including the steps of producing a united laminated sheet from identifiable laminae, reproducing the cut of the plate for the make ready, removing portions of the laminae bodily without separation of the laminae whereby shade gradations of the reproduction correspond to variations in thickness of the make ready constituting the remainder of the united laminated sheet.

8. The process of producing a make ready, including the steps of treating sheets to make the same impervious to variations in atmospheric humidity, binding the treated sheets into a united laminated structure, reproducing the cut of the plate upon the structure, peeling portions of laminated sheets while united from the laminated structure so that the remainder thereof has variations in thickness corresponding to gradations in shade to emphasize shading when used as a make ready.

9. The process of producing make ready, including the steps of waxing sheets to make the same impervious to water, binding the waxed sheets into a united laminated structure, reproducing the cut of the plate upon said laminated structure, peeling portions of the laminated sheets while united from the laminated structure to produce variations in thickness corresponding to gradations in shade in the remainder of the structure to emphasize shading when used as a make ready.

10. The process of producing a make ready including the steps of coating sheets to make the same impervious to variations in atmospheric humidity, binding the coated sheets into a united laminated structure, bodily producing a cut of the plate upon the structure, removing the portions of all the laminated sheets while united underlying the high light areas, bodily removing

portions of the sheets underlying shaded areas to produce a make ready, the thickness of which varies with gradations of shading.

11. A laminated make ready sheet including a base sheet and a plurality of superimposed sheets of different colors, an adhesive binding material including wax for normally holding the sheets together but failing more easily than the sheets, whereby the laminated make ready may have portions of sheets cut and removed bodily by a failure of the binding material.

12. A laminated structure for use in the printing art including a base sheet and a plurality of superimposed sheets, the uppermost of which has an impression printed thereon, and adhesive binding material including wax for normally holding the sheets together but failing more easily than the sheets, whereby the laminated structure may have portions of sheets cut according to the impression thereon and removed bodily by a failure of the binding material. 5

HOMER L. BISHOP. 10
